CLAIM

The ornamental design for a wireless communication device, as shown and described.

DESCRIPTION

FIG. 1 is a perspective view of a wireless communication device showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dashed broken line showing in the views represent boundaries of the claim and form no part of the claimed design. The broken dashed lines depict portions of the wireless communication device that form no part of the claimed design.
